AUTO SAFETY LIGHT

Jack E. Hasselman, P.O. Box 102, Niles, Ill.

Filed Oct. 24, 1965, Ser. No. 87,928

Term of patent 14 years

(Cl. D48—32)

FIG. 1

FIG. 2

FIG. 3

FIG. 4

FIG. 5

FIGURE 1 is a side elevation of an auto safety light showing my new design;

FIGURE 2 is a top plan view thereof;

FIGURE 3 is a frontal elevation thereof;

FIGURE 4 is a rear elevation thereof; and

FIGURE 5 is a bottom plan view thereof.

I claim:

The ornamental design for an auto safety light, as shown.
